(57) **CLAIM**

The ornamental design for a racking system component, as shown and described.

DESCRIPTION

FIG. 1 is a perspective view of the racking system component showing my new design;

FIG. 2 is a front-side and back-side view of the racking system component in FIG. 1;

FIG. 3 is a right-side and left-side view of the racking system component in FIG. 1;

FIG. 4 is a top view of FIG. 1;

FIG. 5 is a bottom view of FIG. 1;

FIG. 6 is a partial, cut away, perspective view of the racking system component in use showing integration with other system components and boards;

FIG. 7 is a perspective view of the racking system component showing my new design;

FIG. 8 is a front-side and back-side view of the racking system component in FIG. 1;

FIG. 9 is a right-side and left-side view of the racking system component in FIG. 1;

FIG. 10 is a top view of FIG. 1;

FIG. 11 is a bottom view of FIG. 1; and,

FIG. 12 is a partial, cut away, perspective view of the racking system component in use showing integration with other system components and boards.

The broken lines shown in FIGS. 1-12 depict portions of the racking system component that form no part of the claimed design.

The additional broken lines in FIGS. 6 and 12 depict how the racking system component may be integrated during use with other components and boards to create the racking system, these figures illustrate environment and the broken lines form no part of the claimed design.

1 Claim, 12 Drawing Sheets
